POWDERED FUEL BURNER

Fernley E. Millett, Blairmore, Alberta, Canada

Application December 16, 1941, Serial No. 423,215

5 Claims. (Cl. 110—28)

The present invention relates to furnaces for burning pulverized fuel.

It has been proposed to burn pulverized coal in domestic heating furnaces. However, the ignition problem has always been a source of difficulty. In an average domestic pulverized fuel furnace, only a fraction of a pound of coal dust is in suspension at any time. It has been found that spark ignition is virtually impossible when starting without the admixture of a secondary fuel such as gas or oil which must be supplied for ignition and used to keep the fire going until the furnace has been heated to normal operating temperature, whereupon the supply of secondary fuel can be cut off.

A primary object of the invention is to provide a pulverized fuel burning furnace in which the pulverized fuel-air mixture may be ignited with electrical ignition without the use of secondary fuels such as gas or oil.

Another object of the invention is to provide a pulverized fuel burning furnace with an electrically heated ignition chamber.

Another object of the invention is to provide a pulverized fuel burner with an electrically heated ignition chamber and a fuel delivery member movable with respect to the ignition chamber so as to be out of range of the ignition chamber during normal operation following ignition.

A further object of the invention is to provide a pulverized fuel burner with electrically operated ignition means capable of supplying a large amount of sensible heat to the mixture of powdered coal and air delivered to the ignition chamber so as to raise the same to ignition temperature when starting the burner into operation.

A still further object of the invention is to provide for automatic operation of the ignition means and relative movement between the ignition means and fuel delivery member to remove the ignition means from the fire zone after the flame is self-sustaining.

Other objects and advantages of the invention will become evident during the course of the following detailed description of a preferred embodiment of the invention as illustrated by the accompanying drawings which form a part hereof and in which:

Fig. 1 is a vertical section through a furnace equipped with a powdered fuel burner embodying the invention.

Fig. 2 is an axial section through the burner proper, and

Fig. 3 is a wiring diagram for the system.

Referring more particularly to the drawings, the invention is shown applied to a hot air furnace 5 having an inner casing 6, the back and bottom walls of which are provided with a refractory lining 7. The products of combustion pass from the main fire chamber within the casing 6 through an economizer 8 to a flue 9. While a hot air furnace has been illustrated it will be understood that any other type such as a hot water or steam boiler type could be provided with the invention.

The burner assembly comprises a refractory lined tubular combustion chamber 11 which extends into the fire chamber within the casing 6 through an opening 12 opposite the fire wall formed by the refractory lining 7, which opening may be the usual fire door opening. A mounting plate 13 closes the space around the chamber 11 which is slanted at an angle of about 30° so that ash or slag formed will not accumulate in the chamber 11.

An ignition chamber 14 is mounted coaxially of the tubular combustion chamber 11 at the upper and outer end thereof and in communication therewith. The chamber 14 is provided with a refractory lining 15 and mounted therein is electric heating element or elements 16 which may be of nickel-chrome wire or other material having suitable electrical and physical properties to withstand high temperatures. The heating element 16 is preferably partially embedded in the surface of the refractory lining 15. The ignition chamber 14 is substantially conical in axial section opening at its base or large end into the combustion chamber 11 and provided at its small end with an axially disposed tubular guide bushing 17 for the outer tube 18 of a double tube powdered fuel burner 19.

The burner 19 includes a T-fitting 20 mounted on the outer end of tube 18 to which secondary air is supplied through a branch pipe 22 which may be provided with a regulating valve 23. An inner fuel delivery tube 24 concentric with tube 18 is supported by fitting 20 and is supplied with a mixture of powdered coal and air through a flexible hose 25 from a mixing blower 26 operated by an electric motor 26'. At its discharge end, which is substantially coincident with the inner or delivery end of tube 18, the fuel-air delivery tube 24 is provided with a propeller shaped whirler 27 for insuring intimate mixture of the powdered coal and air emerging therefrom.

The burner 19 is axially slidable in the bushing 17 so that it may be adjusted to shift its dis-

charge end more or less into and out of the ignition chamber 14, that is, it may be adjusted to a retracted position in which the fuel and air must pass through the ignition chamber after leaving the tubes 18 and 24 or to a projected position in which the tubes extend through the ignition chamber 14 and discharge directly into the combustion chamber 11.

Shifting of the burner between its two extreme positions of adjustment preferably is effected by means of a two position control electric motor 28, of a type commonly used for damper controls and preferably provided with reduction gears giving an output shaft speed of 180 degrees in about 105 seconds and equipped with limit switches providing for 180 degrees output shaft rotation each time energized. A crank arm 29 mounted on the output shaft of motor 28 is connected by a connecting rod 30 to the T-fitting of burner 19 so that with each successive 180 degrees of rotation of the motor shaft 30', the burner is shifted from one end to the other of its limits of movement. In one end position, shown in Fig. 2, the burner is retracted so that it discharges the powdered fuel and air into the end of the ignition chamber remote from the combustion chamber. This is the starting position in which the air and powdered fuel pass entirely through the ignition chamber and being exposed to radiant heat in the ignition chamber are raised to ignition temperature thereby. In the other end position, indicated by dotted lines in Fig. 2, the burner is in the projected position wherein the tubes 18 and 24 extend through the ignition chamber and discharge powdered fuel and air directly into the combustion chamber 11. This is the running position to which the burner is shifted after operating in starting position long enough to insure self-sustained combustion without the aid of the heat supplied in the ignition chamber. Shifting of the burner to discharge directly into the combustion chamber, after starting, saves wear and tear on the heating coils and lining of the ignition chamber by protecting them from the full heat of the pulverized fuel flame during normal running of the furnace.

The electrical control system for the burner is shown diagrammatically in Fig. 3. A definite time relay 31 controls a pair of double throw switches 32 and 33 operated in unison by a solenoid 34. In one position switch 32 energizes burner shifting motor 28 and switch 33 energizes ignition heating coil 16. In the other position switch 32 energizes burner shifting motor 28 again and switch 33 energizes fuel supply motor 26'. A speed control rheostat 35 provided with an adjusting handle 35' is placed in series with motor 26' and a thermostat 36 controls a shunt around the speed controller. This system provides for continuous operation of the burner on a high-low principle, the thermostat 36 shunting out the rheostat 35 when the temperature falls to a point requiring more heat than is being supplied on low fire so that the motor runs at high speed until the demand is satisfied. A manual on-off switch 37 is provided for starting or stopping operation of the burner entirely. If automatic on-off operation is desired, the thermostat 36 and rheostat 35 are eliminated and manual switch 37 is replaced by a thermostat or pressure responsive switch, as desired.

In the operation of the burner, to put the burner into operation switch 37 is closed to energize time delay relay 31. Relay 31 immediately operates to energize solenoid 34 to throw switches

32 and 33 to the start position to energize electric heating element 16 and burner shifting motor 28, which latter operates to rotate its output shaft 180° to shift the burner to the retracted starting position. After elapse of the definite time for which the relay 31 is adjusted, which time is sufficient for the heating coil 16 to become incandescent and raise the temperature of the refractory lining 15 of ignition chamber to incandescence, the relay breaks the circuit of solenoid 34 and the switches 32 and 33 are thrown to the opposite or run position to break the heating coil circuit and energize the fuel supply blower motor 26' and again energize the burner shifting motor 28.

When the switches 32 and 33 are thrown to the run position, fuel and air are supplied to the burner 19 which fuel and air mixture in its passage through the incandescent ignition chamber 14 absorbs heat therefrom and is raised to the ignition temperature so that the fire is started. At the same time, the motor 28 being energized starts operation through another 180° cycle to shift the burner tubes 18 and 24 slowly toward the run position. As the burner advances, the fuel-air mixture is heated to maintain combustion and by the time the burner reaches regular running position, the flame is self-sustaining in combustion chamber 11. The burner then continues in operation in this position until a shutdown calls for a new cycle of operation when again starting up.

Although a preferred embodiment of the invention has been shown and described by way of illustration, it will be understood that the same is not limited to the precise details of construction shown and that various modifications may be resorted to without departing from the spirit of the invention within the scope of the appended claims.

40 I claim:

1. In a powdered fuel burner, a combustion chamber, an ignition chamber opening into the combustion chamber, electrical heating means within said ignition chamber, a fuel delivery means movably mounted with respect to said ignition chamber and said combustion chamber and adapted to be moved to one position to deliver powdered fuel to said ignition chamber at a point remote from said combustion chamber 45 and to another position to deliver fuel directly into said combustion chamber, and means for energizing said heating means and moving said fuel delivery means to the first mentioned position when starting said burner into operation 50 and for moving said fuel delivery means to the second mentioned position and deenergizing said heating means after the fuel has been ignited.

2. In a powdered fuel burner, a combustion chamber, an ignition chamber opening at one end into said combustion chamber, electrical heating means within said ignition chamber, a fuel-air delivery tube movably mounted with respect to and extending into said ignition chamber at a point remote from the combustion chamber, and means for shifting said fuel-air delivery tube with respect to said combustion and ignition chambers between a retracted position in which fuel and air delivered through said tube passes through the ignition chamber to the combustion chamber and a projected position in which fuel and air delivered through said tube is discharged directly into the combustion chamber.

3. In a powdered fuel burner, a combustion chamber, an ignition chamber opening at one end into said combustion chamber; electrical heat-

ing means within said ignition chamber; a fuel-air delivery tube movably mounted with respect to and extending into said ignition chamber at a point remote from the combustion chamber; means for shifting said fuel-air delivery tube with respect to said combustion and ignition chambers between a retracted position in which fuel and air delivered through said tube passes through the ignition chamber to the combustion chamber and a projected position in which fuel and air delivered through said tube is discharged directly into the combustion chamber, and means for controlling the supply of heating current to said electrical heating means, for actuating said shifting means to move said fuel-air delivery tube to the retracted position when starting said burner into operation, for controlling supply of fuel and air to said delivery tube, for advancing said tube to projected position and for cutting off the supply of heating current to said electrical heating means after a predetermined starting period.

4. In a powdered fuel burner, an open ended combustion chamber, an ignition chamber mounted at one end of and opening into said combustion chamber, a bushing at the end of said ignition chamber opposite said combustion chamber, a burner tube slidable through said bushing, electrical heating means within said ignition chamber, means for supplying powdered fuel and air through said burner tube, and means for moving said burner tube through said bushing

6 to a retracted position in which fuel and air delivered thereby is caused to pass through the ignition chamber to the combustion chamber or to a projected position in which fuel and air delivered thereby passes directly into the combustion chamber.

5. In a powdered fuel burner, an open ended combustion chamber, an ignition chamber mounted at one end of and opening into said combustion chamber, a bushing at the end of said ignition chamber opposite said combustion chamber, a burner tube slidable through said bushing, electrical heating means within said ignition chamber, means for supplying powdered fuel and air through said burner tube, and means for moving said burner tube through said bushing to a retracted position in which fuel and air delivered thereby is caused to pass through the ignition chamber to the combustion chamber or to a projected position in which fuel and air delivered thereby passes directly into the combustion chamber, and control mechanism operative to actuate said burner tube moving means to shift the burner tube to retracted position and to energize said electrical heating means when starting the burner into operation and operative after a predetermined time interval to actuate said burner tube moving means to shift said burner tube to projected position, actuate the fuel and air supply means and to deenergize the 10 15 20 25 30 electrical heating means.
